ATTORNEY.

UNITED STATES PATENT OFFICE

FRANCIS HOGG, OF WESLEYVILLE, PENNSYLVANIA, ASSIGNOR TO THE STANDARD STOKER COMPANY, INCORPORATED, A CORPORATION OF DELAWARE

LOCOMOTIVE TENDER

Application filed November 13, 1931. Serial No. 574,777.

This invention relates to appliances for mechanically advancing coal from the rear to the forward portion of the coal bin of a locomotive tender, commonly termed "coal pushers", for placing the coal within convenient reach of the fireman or for delivering it to mechanical means for supply as required to the firebox of the locomotive.

It is an object of the invention to provide a coal pusher, having a reciprocating cross-head or pusher head which is arranged to ride over the surface of the body of coal in the tender bin, moving it forwardly.

It is a further object of the invention to provide a coal pusher of the latter type which is pivoted at its rearward end permitting downward movement about the pivot as an axis as the supply of coal diminishes and upward movement when the supply of coal in the bin is replenished.

It is another object of the invention to provide in a coal pusher appliance, a novel form of pusher rack that is efficient in operation, cheaply manufactured, simple in design and rigid and durable in construction.

A still further object of the invention resides in providing the tender fuel bin with a coal pusher having a centrally and longitudinally extending guide and a pusher member slidably supported in the guide.

Other and further objects and advantages of the invention will become apparent from the following description when read in connection with the accompanying drawings, in which

Fig. 1 is a longitudinal central section through a portion of a locomotive tender showing the improved coal pusher applied thereto;

Fig. 2 is a plan view of the improved coal pusher;

Fig. 3 is a vertical cross sectional view through the forward part of a locomotive tender with the coal pusher applied thereto and shown in its lowermost position;

Fig. 4 is a sectional view on the line 4—4 of Fig. 2;

Fig. 5 is a view in elevation of Fig. 4 with parts broken away;

Fig. 6 is a detail view in longitudinal section of the motor with parts in elevation;

Fig. 7 is a view similar to Fig. 1 showing a modified form of the invention;

Fig. 8 is a sectional view on the line 8—8 of Fig. 6; and

Fig. 9 is a view in elevation of Fig. 8 with parts broken away.

In the drawings, referring particularly to the preferred form of the invention illustrated in Figures 1 to 6, the locomotive tender is indicated generally by the numeral 10 provided with the fuel bin 11 and the water compartment 12. Separating the fuel bin 11 and the water compartment 12 are the rear slope sheet 13, the side slope sheets 14 and 15 and the fuel bin floor 16.

The coal pushing device, generally indicated by the numeral 17 is pivotally mounted at the central upper portion of the rear slope sheet 13. The motor 18 of the coal pushing device 17 comprises the cylinder 19, the cylinder head 20 and the piston 21 fitted in the cylinder 19. The cylinder 19 is provided with transversely extending trunnions 22 and 22a which are arranged to be received in and rotatable in the bores 23 in the pillar blocks 24. The pillar blocks 24 are securely fastened in any suitable manner to the rear slope sheet 13. Secured to the piston 21 is the piston rod 25 which passes through a stuffing box 26 in the cylinder front head 27. A guide 28 for the piston rod 25 is securely attached to the cylinder front head 27 as by bolts 29.

A plurality of cross heads 30 are secured to the piston rod 25 by means of the piston rod keys 25a and are arranged for slidable movement in the piston rod guide 28 during reciprocatory motion of the piston rod 25. Depending from and rigidly attached to the cross heads 30, as by welding or bolting, is the pusher rack 31. The pusher rack 31 is preferably, though not necessarily, formed by tying together a series of transversely extending angle irons 32 by means of the longitudinally extending tie bars 33. It will be obvious that the design, shape and form of the pusher rack and the particular kind of cross bars and tie bars composing it may be greatly varied as desired to provide a construction that is

lighter or heavier, fabricated or cast in one piece as conditions demand.

In the preferred form of the device the pusher appliance rests on the top surface of the body of coal, and as the piston rod 25 reciprocates it moves the pusher rack 31 forward and backward across the coal pushing it forward toward the coal gate (not shown) of the tender. The angle irons 32 are preferably 5 of V-shape, the pushing face of the V having a greater angularity so that as the rack moves forward the steep pushing face of the V digs into the coal pushing it forward and as the rack moves backward the flatter face of the V 10 rides over the coal.

Motion is imparted to the motor 18 by a fluid, preferably steam, from the locomotive boiler or any other suitable source of supply through the pipes 34 and 35 which serve alternately as both intake and exhaust lines to their respective sides of the piston 21. The trunnions 22 and 22a are provided with the 15 passages 36, 36a arranged to receive the pipes 34 and 35 respectively. The passages 36, 36a 20 communicate with the ports 37, 37a respectively in the cylinder 19, one port 37, opening into the cylinder adjacent the cylinder backhead and the other port 37a opening into the cylinder adjacent the cylinder 25 front head. Thus, when steam is passed through the pipe 34, passage 36 and port 37 to the cylinder, the piston 21 is moved forward thereby pushing the piston rod 25 and its attached pusher rack 31 forward and the 30 port 37a, passage 36a and pipe 35 becomes the exhaust line. When steam is passed through the pipe 35, passage 36a and port 37a to the cylinder, the piston 21 is moved back thereby pulling the piston rod 25 and pusher rack 31 35 back to its original position and the port 37, passage 36 and pipe 34 then becomes the exhaust line. A valve (not shown) preferably arranged in the locomotive cab, controls the supply of steam to one of the pipes 34, 35 or 40 the other.

The central top portion of the rear slope sheet 13 is cut out as at 38 to provide clearance for the motor 18 when the pusher device is raised. Suitable means, such as the windlass 39, is provided for lifting the pusher device when the supply of fuel in the bin 11 is replenished. The weight of the pusher device causes it to fall by gravity about the trunnions as an axis as the supply of coal 45 in the bin diminishes.

In Figures 7, 8, and 9 is illustrated a modified form of the invention in which the pusher device is rigidly fixed to the rear slope sheet 13 at its rearward end and to the fuel bin floor 16 at its forward end and operates beneath the body of coal in the tender bin. As in the preferred form of the invention the pusher rack 31 is rigidly secured to the piston rod 25 through the cross heads 30, which 50 are slidably supported in the guide 28. In

this form of the device the angle irons 32 forming the pusher rack 31 are preferably of an inverted V-shape, though it will be obvious that the design, shape and construction of the pusher rack members may be altered without departing from the scope of the invention. The guide 28 may be fixed to the floor of the tender bin by suitable means, as by the bracket 40, and the motor 18 is fixed to the upper rear portion of the 55 rear slope sheet 13 by suitable means.

I claim:

1. The combination with a locomotive tender having a fuel bin, of a reciprocable pusher for moving the fuel to the forward end of the bin pivotally mounted in said bin. 80

2. The combination with a locomotive tender having a fuel bin, of a pusher for moving the fuel to the forward end of the bin, said pusher being arranged to rest on the surface of the fuel in said bin and means imparting reciprocatory motion to said pusher. 85

3. The combination with a locomotive tender having a fuel bin, of a pusher for moving the fuel to the forward end of the bin, said pusher being arranged to rest on the surface of the body of fuel in said bin and to move downwardly with it as the supply therein is depleted, and means imparting reciprocatory motion to said pusher. 90

4. In a locomotive tender coal pusher, the combination of a motor having a cylinder, a piston fitting in said cylinder, a piston rod attached to said piston and extending forwardly beyond said cylinder, a guide for said piston rod and a pusher rack depending and supported from said piston rod. 100

5. In a locomotive tender, a fuel bin having an inclined rear wall and a floor, a coal pusher for moving the coal to the forward end of the bin comprising a pusher rack arranged to reciprocate along said rear wall, and means for imparting reciprocating motion to said rack, said coal pusher being fixed at its rearward end to said rear wall and at its forward end to said floor. 105

6. In a locomotive tender, a fuel bin having an inclined rear wall, a pusher rack arranged to reciprocate along said rear wall, a centrally and longitudinally extending piston rod parallel to said rear wall, said piston rod being fixed to said pusher rack, and a guide for said piston rod fixed at its upper and lower ends. 115

7. In a pusher device the combination of a longitudinally extending piston rod, a guide for said piston rod, cross heads fixed to said piston rod and slidably mounted in said guide, transversely extending angular pusher bars depending from and secured to said cross heads and means for imparting reciprocating motion to said piston rod. 120

8. In a pusher device the combination of a longitudinally extending piston rod, a 130

- guide for said piston rod, a plurality of cross heads fixed to said piston rod and slidably mounted in said guide, a plurality of transversely extending V-shaped bars depending from and rigidly secured to said cross heads, a plurality of longitudinally extending bars arranged to tie said V-shaped bars together and means for imparting reciprocating motion to said piston rod. 5
9. The combination with a locomotive tender having a fuel bin, of a reciprocable pusher for moving the fuel to the forward end of the bin pivotally mounted at its rearward end in the rearward portion of the bin and means at the forward portion of the bin for raising said pusher about its pivotal mounting. 10
10. In a locomotive tender coal pusher, the combination of a motor having a cylinder, a piston fitting in said cylinder, a piston rod attached to said piston and extending forwardly beyond said cylinder, a guide for said piston rod, a cross head rigidly secured to said piston rod and slidably mounted in said guide, and a pusher rack depending from and secured to said cross head. 15
11. In a locomotive tender coal pusher, the combination of a motor having a cylinder, a piston fitting in said cylinder, a piston rod attached to said piston and extending forwardly beyond said cylinder, a guide for said piston rod, a plurality of cross heads rigidly secured to said piston rod and slidably mounted in said guide, and a plurality of transversely extending angular bars depending from and secured to said cross heads. 20
12. In a locomotive tender coal pusher, the combination of a motor having a cylinder, a piston fitting in said cylinder, a piston rod attached to said piston and extending forwardly beyond said cylinder, a guide for said piston rod, a plurality of cross heads keyed to said piston rod and slidably mounted in said guide, a plurality of transversely extending V-shaped bars depending from and rigidly secured to said cross heads, and a plurality of longitudinally extending bars arranged to tie said V-shaped bars together. 25
13. In a locomotive tender, a fuel bin having an inclined rear wall, support members rigidly mounted on said rear wall, a coal pusher comprising pushing means and a motor for operating said pushing means, transverse extensions from said motor received in said support members and arranged therewith for pivotally supporting said coal pusher. 30
14. In a locomotive tender a fuel bin having an inclined rear wall, support members rigidly mounted on said rear wall, a coal pusher comprising a reciprocating motor, lateral extensions from said motor received in said support members and arranged therewith for pivotal movement of said motor and coal pushing means secured with and actuated by said motor. 35
15. In combination, with a tender fuel bin having an inclined rear wall, of support members at the rear of said rear wall, a fluid pressure cylinder, lateral extensions from said cylinder received in said support members and arranged therewith for pivotal movement of said cylinder, a piston reciprocating in said cylinder and coal pushing means connected to said piston and arranged to be reciprocated thereby. 40
16. The combination, with a tender fuel bin having an inclined rear wall, of support members at the rear of said rear wall, a fluid pressure cylinder, lateral extensions from said cylinder received in said support members and arranged therewith for pivotal movement of said cylinder, a piston reciprocating in said cylinder, passages in said lateral extensions communicating with said cylinder at opposite sides of said piston, pressure fluid lines communicating with said passages and coal pushing means connected to said piston and arranged to be reciprocated thereby. 45
17. In a locomotive tender having a fuel bin with an inclined rear wall and a coal pusher, support members for said coal pusher rigidly secured to said rear wall, a motor for said coal pusher, a cylinder for said motor, transversely extending projections from said cylinder arranged to be pivotally mounted in said support members, a front head for said cylinder, a piston in said cylinder, a piston rod attached to said piston and extending forwardly through and beyond said cylinder front head, a guide for said piston rod rigidly secured to said cylinder front head and a pusher member depending from and supported from said piston rod. 50
18. The combination, with a tender fuel bin having an inclined rear wall and a floor, of a fluid pressure cylinder fixed at the rear of said rear wall, a piston reciprocating therein, a piston rod connected to said piston and extending forwardly parallel with said rear wall, a guide for said piston rod fixed at its rearward end with said cylinder and at its forward end to said fuel bin floor, and a pusher member depending from and supported from said piston rod. 55
19. In a locomotive tender having a fuel bin with an inclined rear wall, a coal pusher comprising a reciprocating pusher member and pressure fluid operated means imparting reciprocating motion to said pusher member, a pivotal connection for mounting said coal pusher from said rear wall, passages in said pivotal connection communicating with said pressure fluid operated means and a pressure fluid lead delivering to said passages. 60
20. In a locomotive tender having a fuel bin with an inclined rear wall, a coal pusher comprising a reciprocating pusher member and a pressure fluid operated motor imparting reciprocating motion to said pusher member. 65

ing reciprocating motion to said pusher member, means for pivotally mounting said coal pusher on said rear wall, a cylinder for said motor, passages in said pivotal means communicating with said cylinder and pressure fluid leads delivering to said passages.

5 In testimony whereof I affix my signature.
FRANCIS HOGG.
